SUPPORT ARRANGEMENT

Werner A. Bruder, Stuttgart-Schonberg, Germany, assignor to Daimler-Benz Aktiengesellschaft, Stuttgart-Unterturkheim, Germany

Filed Aug. 16, 1960, Ser. No. 49,919

Claims priority, application Germany Aug. 28, 1959

7 Claims. (Cl. 60—39.31)

The present invention relates to the construction and arrangement of the securing base or foot portion of jet propulsion units arranged in a freely exposed manner, and more particularly relates to the construction and arrangement of the securing base or foot portion of jet propulsion units, especially of ram jet propulsion plants preferably having an elliptical or quasi elliptical cross-section and arranged along the outwardly disposed ends of the propeller or rotor blades of helicopters.

The ram jet propulsion units arranged at the ends of the propeller or rotor blades which consist essentially only of a sheet-metal casing or envelope serving as combustion chamber, and which are provided in the front thereof with a double-walled inlet diffuser and at the rear end thereof with a nozzle-shaped constriction, are subjected during the operation thereof to relatively high centrifugal forces and stresses. Even though the propulsion unit housing or casing is cooled on the outside thereof by the air flowing past the same, the rigidity of the housing or casing nevertheless suffers by reason of the relatively high temperatures prevailing at the inside thereof. Additionally, the propulsion unit housing is normally constructed of relatively thin walls for reasons of weight-saving.

It is already known in the prior art to construct the housing of ram jet propulsion units arranged at the ends of the propeller or rotor blades of elliptically-shaped or quasi-elliptical cross-section in order to maintain as small as possible the deformation of the housing during operation.

The problem with which the present invention is concerned consists in so constructing the supporting base or foot portion of the propulsion unit, preferably of one having an elliptical or quasi elliptical cross-section in such a manner that not only high rigidity properties are attained but also favorable conditions are created as regards cooling of the sector of the housing facing the support arrangement or facing the propeller or rotor blade end.

It is proposed as solution to the problem in accordance with the present invention to construct the aforementioned housing sector as a double-walled support body which is open to the air flow.

According to another feature of the present invention, it is proposed to rigidly connect with each other the inner and outer wall parts of the housing sector by means of intermediate profile members which form simultaneously flow channel air passages so that a bearer member of lattice or trussing-type framework results therefrom.

Accordingly, it is an object of the present invention to provide a support base for a jet propulsion unit, especially for a ram jet propulsion unit arranged at the outer ends of the propeller or rotor blades in helicopters which obviates the disadvantages and shortcomings of the prior art construction.

It is another object of the present invention to provide a support base and housing construction for a jet propulsion unit of the type described hereinabove in which the forces and resulting stresses, especially the centrifugal forces and stresses resulting therefrom, can be readily absorbed notwithstanding the light-weight properties of the housing.

Another object of the present invention resides in the provision of a support arrangement for a jet propulsion unit of the type described hereinabove which is of rela-

2

tive light weight and provides adequate cooling not only of the outer housing walls but also of the inner walls of the combustion chamber facing the supporting base.

A still further object of the present invention resides in the provision of a light weight housing for jet propulsion units which minimizes the possibility of deformations that may otherwise occur during operation of the unit.

A further object of the present invention resides in the provision of a jet propulsion unit housing which offers high rigidity characteristics in addition to favorable conditions with respect to cooling of the construction thereof.

These and other objects, features and advantages of the present invention will become more obvious from the following description when taken in connection with the accompanying drawing which shows in the single FIGURE thereof, for purposes of illustration only, one embodiment in accordance with the present invention.

Referring now to the drawing which shows in the single figure thereof a cross-sectional view through a portion of a ram jet propulsion unit with the cross-section thereof taken perpendicularly to the longitudinal axis thereof, reference character F generally designates the base or foot portion of the ram jet propulsion unit which itself is generally designated by reference character S. The base F of the jet propulsion unit S is detachably connected or secured, in any known suitable manner, with the propeller or rotor end 11. The sector of the drive unit housing facing the propeller or rotor blade end 11 is constructed as a bearer body generally designated by reference character T and consists essentially of an outer wall part 12 and of an inner wall part 13 which are rigidly connected with each other by means of intermediate profile members 14. As indicated in the single figure of the drawing, the body T has an arcuate extent less than half the arcuate extent of the combustion chamber.

The base F further consists of two sheet-metal web plates 15 and 16 extending in the direction of the longitudinal axis of the propulsion or drive unit which are reinforced with each other by means of transverse web portions 17. The center sections 15' and 16' of the two sheet-metal web plates 15 and 16 are rigidly connected each with the ends 12' and 12'', respectively, of the outer wall parts 12, and thereby constitute in effect a continuation of the latter. The ends 15'' and 16'' of the sheet-metal web plates 15 and 16, the ends 13' and 13'' of the inner wall parts 13 and the ends 18' and 18'' of the housing sector 18 opposite the support base F form a common securing or fastening joint and are connected with each other in any suitable manner, for example, by welding.

Holder or support members 19 are rigidly inserted into the inner wall part 13 for purposes of supporting thereon a central flame holder 20.

The bearer body T is open in the front and in the rear thereof so that the air can flow freely through the channels 21 to thereby cool the walls thereof.

According to the embodiment illustrated in the single figure of the drawing, the support or bearer body member T is locally interrupted for purposes of extending therethrough a spark plug 23, and an insert body member 22 for the spark plug 23 is rigidly secured, for example by welding, in this local interruption.

While I have shown and described one embodiment in accordance with the present invention, it is understood that the same is not limited thereto but is susceptible of many changes and modifications within the spirit and scope of the present invention, and I, therefore, do not wish to be limited to the details shown and described herein, but intend to cover all such changes and modifications as are encompassed by the scope of the appended claims.

I claim:

1. A base construction for the support of a freely exposed propulsion unit, especially of a propulsion unit arranged at the outwardly disposed end of a propeller blade of a helicopter, comprising housing means forming a combustion chamber and including a plurality of housing sectors, support means for supporting said housing means on said outwardly disposed end, one of said factors facing said support means and comprising wall parts including an outer wall part and an inner wall part defining a space therebetween for the flow of air, means for rigidly reinforcing said wall parts and for providing channels for said flow of air comprising profile members connecting said outer wall part and said inner wall part, said support means comprising web plate means secured to said outwardly disposed propeller end, said outer wall part being of less arcuate extent than said inner wall part, said web plate means engaging the ends of said outer wall part and comprising plate portions extending past said outer wall part ends into further engagement with 20 said housing means.

2. A base construction for the support of a freely exposed propulsion unit according to claim 1, wherein said inner wall part is provided with support means supporting therein a flame holder.

3. A base construction for the support of a freely exposed propulsion unit according to claim 1, wherein the housing sector opposite said support means is provided with the end portions extending in directions toward said outwardly disposed end of said propeller blade, and 30 wherein said last-mentioned two end portions, the two ends of said inner wall part and the ends of said plate portions are rigidly connected with each other at a common place.

4. A base construction for the support of a freely 35 exposed propulsion unit according to claim 1, wherein

5 the housing sector opposite said support means includes two end portions extending in directions toward said outwardly disposed end of said propeller blade, said two end portions being rigidly connected with said inner wall part and with said web plate means.

10 5. A base construction for the support of a freely exposed propulsion unit according to claim 1, wherein said plate portions define with said inner wall part further spaces for the flow of air.

15 6. A base construction for the support of a freely exposed propulsion unit according to claim 5, wherein said profile members comprise portions thereof disposed in said further spaces.

7. A base construction for the support of a freely exposed propulsion unit according to claim 6, wherein said portions of said profile members are in connecting relationship with said inner wall part and said plate portions.
